[57] CLAIM

The ornamental design for a drive for moving a gate of a garage, as shown and described.

DESCRIPTION

FIG. 1 is a top plan view of a first embodiment of a drive for moving a gate of a garage according to my invention;

FIG. 2 is a bottom plan view thereof;

FIG. 3 is a left side elevational view thereof;

FIG. 4 is a right side elevational view thereof;

FIG. 5 is a front elevational view thereof; and

FIG. 6 is a rear elevational view thereof;

FIG. 7 is a top plan view of a second embodiment of a drive for moving a gate of a garage according to my invention;

FIG. 8 is a bottom plan view thereof;

FIG. 9 is a left side elevational view thereof;

FIG. 10 is a right side elevational view thereof;

FIG. 11 is a front elevational view thereof; and,

FIG. 12 is a rear elevational view thereof.
